MILO HARRIS, OF JAMESTOWN, NEW YORK.

Letters Patent No. 106,155, dated August 9, 1870.

IMPROVEMENT IN HEMMER FOR SEWING-MACHINE.

The Schedule referred to in these Letters Patent and making part of the same

To all whom it may concern:

Be it known that I, MILO HARRIS, of Jamestown, in the county of Chautauqua and State of New York, have invented a new and useful Improvement in Hemmers; and I do hereby declare that the following is a full, clear, and exact description thereof, which will enable others skilled in the art to make and use the same, reference being had to the accompanying drawing forming part of this specification.

This invention consists in the arrangement of a forming or guide-block, with a scroll-plate for turning the edge of the goods to be hemmed, said block being provided with spiral ridges, as and for the purpose hereinafter set forth.

Figure 1 is a plan view of my improved hemmer, partly sectioned;

Figure 2 is a side elevation; and

Figure 3 is a section on the line $x x$ of fig. 1.

Similar letters of reference indicate corresponding parts.

A represents the supporting plate, and

B, the scroll-plate.

C is the former or guiding-block, which I propose to combine with the scroll-plate in the manner shown. It is provided with spiral ridges on the top and the side next the termination a of the scroll-groove. These ridges are pitched toward the said termination of the groove, and they, or the grooves between them, are

cut or otherwise formed with especial reference to having the edges so shaped that the fabric will slide over them to the bottom a freely, but will be held by them against moving back.

The fabric is drawn over this block by the feeder, and by the action of the presser-foot, with considerable tension, so that the projections guide it downward to the bottom of the groove.

The block is attached to the horizontal part of the scroll-plate O, near its termination, and forms the termination of the grooves.

By reason of the feeding action of this block I am enabled to make the space between it and the scroll-plate B wider than could be done without it, so that heavy seams may be passed through it, which is particularly desirable, especially when hemming bias goods which have been seamed together.

Having thus described my invention,

I claim as new, and desire to secure by Letters Patent—

The block C, provided with spiral grooves or ridges, and arranged near the termination of the scroll-plate B, on the horizontal part of the same, as and for the purpose specified.

MILO HARRIS.
